UNITED STATES PATENT OFFICE

ISAAC W. BONIC, OF MILWAUKEE, WISCONSIN

SCORING DEVICE

Application filed May 3, 1930. Serial No. 449,601.

This invention relates to improvements in scoring devices and more particularly to a pocket scoring device.

One of the objects of this invention is the provision of a scoring device particularly adapted for personal use to be carried about in the pocket, and is especially laid out for the purpose of keeping baseball scores of the various teams and is so constructed whereby the teams are interchangeable on the board so that the score of any two teams can be readily registered on the cards.

Another object of the present invention is the provision of a scoring device which includes a folder in which the various teams are arranged with scoring cards upon opposite sides of the folder, and means is provided whereby two of the teams can be positioned at the ends of the scoring cards, particularly the teams which are playing, and it is desired to keep the score of such teams as are playing, the registry of the teams being interchangeable within the folder so that any two teams can be positioned at the ends of the scoring cards.

A further object of the invention is the provision of a scoring device which can be easily adapted into suitable form for carrying about in the pocket, or can be adapted for home use for keeping baseball scores which are broadcast by radio, and the teams are interchangeable on the scoring device so that the score can be readily recorded of any two playing teams.

With the above and other objects in view, the invention consists in the novel features of construction, the combination and arrangement of parts hereinafter more fully set forth, pointed out in the claims and shown in the accompanying drawings wherein:

Figure 1 is a plan view of a scoring device constructed in accordance with my invention, illustrating the same open for use and parts thereof broken away and illustrated in cross section;

Figure 2 is an end elevation illustrating the device in a folded position;

Figure 3 is a detailed plan view illustrating a slightly modified form; and

Figure 4 is a section on the line 4—4 of Figure 3.

This invention as stated heretofore pertains to scoring devices and is particularly constructed so that the same can be made on a small scale to be carried about in the pocket when attending a ball game, so that each individual may have his own score card, and the device can be used equally as well for scoring baseball games broadcast by radio, so that a person may use the device when at home and receiving the results of a ball game over a radio.

In the form of the invention illustrated in the drawings it will be noted that the scoring sheets are enclosed in a suitable folder which can be easily carried about in the pocket and this folder comprises the two side members 1 and 2 connected by means of a flexible board 3, so that the members 1 and 2 can be easily folded to a parallel position, as shown in Figure 2.

Attached to each of the side members 1 and 2, is a pocket 4 which may be of the same material as the covering for the members 1 and 2, or may be of any desired material and received within these pockets are the back boards 5 of the scoring pads 6. This scoring pads which consists of a plurality of sheets are attached to the back portions 5 by means of the small staples 7, and in fitting the scoring pad within the folder, it will be noted that the back portion 5 is inserted into the pocket 4, so as to retain the scoring pad, as illustrated in Figure 1.

As a general rule with the various baseball leagues throughout the country, each league has a membership of eight teams and the names of the players of each team are indicated on separable strips 8, and these strips are carried by individual cards 9, each card

carrying the names of the players of each team. The cards 9 are preferably of light cardboard or other similar material and provided at each end with socket fasteners 10 adapted to engage the yieldable head members 11 carried by the outer wall of each pocket 4, as illustrated in Figure 1.

Each of the team cards 9 are provided with retaining loops which may be applied to these cards 9 in any suitable manner, but in order to provide a comparatively inexpensive product, parallel rows of looped stitching is applied to each card adjacent each longitudinal edge, and this type of stitching provides a plurality of loops 12 adapted to receive the ends of the strips 8 upon which the names of the players are indicated. There are various ways in which the strips 8 can be removably applied to the cards 9, but as stated heretofore, for the purpose of producing a comparatively cheap product, the rows of stitching are applied to each card 9. At one end of each card, a loop 13 is provided adapted to be grasped by the hand for removing the cards from the outer wall of each pocket 4.

As illustrated in Figure 1, there is provided a suitable folder for an eight-team baseball league and each team is represented upon a team card 9, and attention is directed to the fact that the scoring pads 6 are somewhat smaller than the folder, thus leaving a space 14 at the ends of the side portions 1 and 2, so that one team on each side portion will be exposed, but the other three teams on each side portion will be covered by the pad 6, the two exposed team cards containing the names of the teams and the players on the teams which are playing, and the scoring pads are provided with individual sheets on which is indicated by means of transverse and longitudinal lines a plurality of sections 15.

The scoring sheets are preferably printed in the usual well known manner and each longitudinal section is aligned with an individual strip 8 on which a player's name is indicated, so that the record of this player may be kept in its proper column on each scoring sheet.

It will be noted that the top strip 8 on each team card 9 has indicated thereon the name of the ball team listed thereon, while the remaining strips have indicated thereon the various players and due to the fact that practically all of the teams carry a number of utility players, it will be apparent that the strips 8, bearing the names of these utility players can be attached to the rear of each team card, and when one of the regular players is removed from the game and a utility player substituted, the strips bearing these names can be displayed in their proper positions with very little difficulty.

Any number of loops 12 can be formed upon each card so that the regular number of 9 players can be placed in position with pro-

tection for two or more utility players, so that the score of these utility players may also be recorded upon the sheets of each score pad.

It will be noted that the folder which comprises the two side portions 1 and 2 can be used for a great length of time, and if this folder is constructed of a suitable wear resisting material, it will last for a long time, and due to the fact that the scoring sheets are arranged in pad form, with a comparatively heavy back portion 5, the pads after the number of sheets thereon have been used, can be quickly replaced with new pads, and while the pockets 4 have been illustrated as suitable means for retaining the pads in position, it will be apparent that various other ways may be provided for removably securing these pads within the folder.

In using the scoring device, it will be noted that the team cards 9 which are not in use will be positioned beneath the pad 6, while the two teams playing can be positioned in the space 14 and these two teams in the space 14 can be quickly interchanged for any of the other teams beneath the pad 6, as they are removably attached to the outer wall of the pocket 4, while the team cards 9 in the space 14 are attached directly to the side portions 1 and 2.

In Figures 3 and 4, I have illustrated a slightly modified form of the invention which is particularly adapted for use wherein a team has a tendency to change pitchers a great number of times during the progress of the game, and in this form of the invention, there is attached to the side portions of the folder spaced brackets 16, and rotatably mounted within these brackets are the parallel shafts 17 upon which is wound an endless sheet 18 on which the names of the various pitchers, carried by each team, is indicated, and it will be noted that one end of each shaft 17 is provided with a thumb wheel 19, so that the sheet 18 can be moved in either direction for bringing into view the pitcher who is actively engaged in the game being scored. This mechanism illustrated in Figures 3 and 4 can be carried by the team cards 9 and positioned over the fastening members 10, as shown in Figure 3. It will be noted that in order to correctly use the above device, the thumb wheels 19 can be grasped by the fingers and by turning the parallel shafts 17 any one of the names on the endless sheet can be brought into view as shown in Figure 3.

It will be apparent from the foregoing that I have provided a comparatively simple and inexpensive pocket scoring device which can be made up in interchangeable pads and interchangeable team cards, so that each individual will have its own score card and readily arrange the team cards to position the active teams at one end of the scoring pads for each game played.

It will be apparent that the device can be made up in a similar manner to be used at home in connection with the radio where it is desired to keep the score of baseball games broadcasted by the radio, and in forming a scoring device for home use, the side pieces 1 and 2 can be formed in a single piece and the scoring sheets also be made in a single piece with the scoring sections of each team divided.

It will be noted in Figures 1 and 2, that the name strip on which the name of the team is printed is positioned in alignment with a series of sections 15' which can be used for tabulating the total score of each inning during the game, and if found desirable, these sections can also be used for tabulating the number of hits for each inning.

While I have shown and described the preferred embodiment of my invention, it will be apparent that slight changes may be made in the construction when putting the invention into practice without departing from the spirit of the same or the scope of the appended claims.

I claim:

1. A scoring device including a folder having flexibly connected side portions, interchangeable team cards carried by said side portions and interchangeable name strips carried by said cards.

2. A scoring device including a folder having flexibly connected side portions, interchangeable team cards carried by said side portions and interchangeable name strips carried by said cards, a removable pad carried by each side portion and comprising a plurality of superposed sheets having sections thereon adapted to be aligned with the name strips.

3. A scoring device comprising a folder having flexibly connected side portions, team cards arranged in parallel relation and detachably connected to the side portions, name strips removably carried by said team cards and a plurality of score sheets detachably supported by the side portions and normally covering all of the team cards on each side portion with the exception of one remaining exposed at one end of the scoring sheets.

4. A scoring device including a supporting element, team cards arranged in parallel relation and removably attached thereto, name strips removably carried by said cards and a scoring pad comprising a plurality of superposed sheets mounted on said supporting element and normally covering all of the team cards except one which is exposed at one end of the scoring pad, and said scoring pad having a plurality of sections adapted to be aligned with the name strips on the exposed team card.

5. A scoring device including a folder having flexibly connected side portions, a pocket carried by each side portion, a removable pad

having a relatively stiff back part adapted to be inserted in one of the pockets, interchangeable team cards carried by said side portions and interchangeable name strips carried by said cards and said pad including a plurality of superposed sheets having sections thereon adapted to be aligned with the name strips.

In testimony that I claim the foregoing I have hereunto set my hand at Milwaukee, in the county of Milwaukee and State of Wisconsin.

ISAAC W. BONIC.
